CLAIM

The ornamental design for a fixed-wing VTOL aerial vehicle, set as shown and described.

DESCRIPTION

FIG. 1 is a left side and top front perspective view of the fixed-wing VTOL aerial vehicle, the right side and top front perspective view being a mirror image thereof;

FIG. 2 is a left side and top rear perspective view of the fixed-wing VTOL aerial vehicle of FIG. 1, the right side and top rear perspective view being a mirror image thereof;

FIG. 3 is a front view of the fixed-wing VTOL aerial vehicle of FIG. 1;

FIG. 4 is a rear view of the fixed-wing VTOL aerial vehicle of FIG. 1;

FIG. 5 is a left side and bottom front perspective view of the fixed-wing VTOL aerial vehicle of FIG. 1, the right side and bottom front perspective view being a mirror image thereof;

FIG. 6 is a left side and bottom rear perspective view of the fixed-wing VTOL aerial vehicle of FIG. 1, the right side and bottom rear perspective view being a mirror image thereof;

FIG. 7 is a plan top view of the fixed-wing VTOL aerial vehicle of FIG. 1;

FIG. 8 is a plan bottom view of the fixed-wing VTOL aerial vehicle of FIG. 1; and,

FIG. 9 is a right side view of the fixed-wing VTOL aerial vehicle of FIG. 1, the left side view being a mirror image thereof.
